ACTUATING MECHANISM FOR MECHANICAL
PENCILS

Joseph Gartenmann, Zurich, Switzerland

Application August 15, 1949, Serial No. 110,265
In Switzerland July 26, 1948

3 Claims. (Cl. 120—14.3)

1

This invention relates to an actuating mechanism on mechanical pencils of the type in which the writing leads are housed in cells formed by slots in the shaft of the pencil. The slots are kept in closed or open condition by means of a selecting mechanism. In the open condition of any one cell the lead may, due to its weight, and by proper positioning of the pencil, be brought from one cell into a feeder and firmly fixed therein in writing position or brought back from the feeder into its cell.

The actuating mechanism acts upon a selecting member which is rotatably disposed and is axially slideable, and is connected or coupled in known manner with the selecting mechanism and the lead feeder. The operative movements of the selecting member depend on the working position of the feeder. The selecting member is locked against undesirable rotation and undesirable movements in axial direction.

The lead feeler commonly used resiliently opens when moved in axial direction by the actuator button and closes to its initial position when returned by spring pressure upon the selecting member, upon release of the actuator button. Thereby the feeder serves in the opening stroke to engage a lead coming from a simultaneously opened cell, or to release a lead gripped in writing position to cause it to fall back into its cell, which is open when the feeder is open.

The actuating mechanism of mechanical multi-lead pencils of the described type which acts on a selecting member locked against undesirable rotation and axial movement is, according to this invention, characterized in this that the selecting member is arranged to include locking means and the inner cylindrical surface of the shaft contains guide-slots, which are provided with an axially extending free zone and an axially extending locking zone. The locking means are disposed in relation to the guide-slots in such manner that they resiliently ride in circumferential direction over the guide-slots by rotation of the selecting member when said locking means are in cooperative position with the guide-slots in the free zone, the selecting member being locked against axial displacement while the locking means are located between two guide-slots, and conversely when said locking means is positioned in the guide-slots the selecting member is capable of moving axially against spring-pressure, and further that when the locking means is positioned in the locking zone of said guide-slots the selecting member is locked against rotation and is free to move in axial di-

2

rection. The selecting member with the locking means in the free zone is rotatable clockwise or counter-clockwise. The locking means positively snap into the guide-slots indicating that it is in position for axial displacement, and the actuator-button per se does not participate in the locking effect to which the selecting member is subjected.

The actuator button may be detachably coupled with the selecting member so as to be freely rotatable when the pencil contains in its feeder a firmly gripped lead. This feature is useful in that no mechanical stress is exerted on any member of the pencil when the actuator button is being rotated inadvertently. The actuator button may be removable from the pencil, and may include means which are operative for a useful purpose.

When the design of the actuating mechanism provides for a button which is rigidly attached to the selecting member it may contain a removable portion which is operative for a useful purpose.

The various features and advantages of this invention will be apparent from the specification and the drawing, in which:

25 Fig. 1 is an elevational section of an actuating mechanism embodying the invention.

Fig. 2 is a cross-section along the line II—II of Fig. 1.

Fig. 3 is an actuator button of a different design, from that shown in Fig. 1.

Fig. 4 shows an actuator button with a removable portion which is formed to constitute a pencil sharpener.

Fig. 5 is a detail pertaining to the feature of a removable actuator button as seen on line V—V of Fig. 1 in the direction of the arrow.

Fig. 6 illustrates in an axial section the actuating mechanism together with the mechanism which is actuated to select and guide a lead.

40 In the particular embodiment of mechanism according to the invention illustrated herewith, 1 is the housing of the actuating mechanism and also the continuation of the body 2 of the pencil. The portion of the body between the feeder and the housing 1 is formed with longitudinal slots in longitudinal direction on the inside cylindrical surface, which slots register with cells capable of being opened and closed by a selecting mechanism. The lead in each cell can be transferred between the cell and the feeder in either direction. 3 indicates the selecting member of the known selecting mechanism connected in one of various known manners to the latter and the feeder. 4 designates a portion of

45 another part of the selecting mechanism. The 50 55

member 4 and the feeder are no part of this invention. The part 5 is a tubular spacer which fixedly retains a disc 6 in its position—shown in Fig. 1. 19 designates the top part of the pencil housing and may be made integral with the latter, or as shown on the drawing, it may be a bushing with outer threads engaging inner threads of the housing 1. Between shoulder 19a of bushing 19 and the top edge of the housing 1 is clamped fast a clip 19b—as fragmentarily shown in section on the drawing. The selecting member 3 is under the influence of a coil pressure spring 13 and contains according to this invention locking means which cooperate with guide slots 7, on the inner cylindrical surface of bushing 19—which is a part of the housing. The locking means on the selecting member 3 consist of a cross-bore 3a through the axis of the cylindrical member 3, which bore contains a spring 9, a pin 10 and two spheres 8. The spheres 8 are pressed against the axially extending slots 7 provided on the inner cylindrical surface of the tubular bushing 19. The diameter *b* in the portion or locking zone B (see Fig. 1) of the inner cylindrical surface of the housing, upon which the member 3 is slidingly fitted, is smaller than the diameter *a* (see Fig. 2) in the portion or free zone A. In the locking zone B the selecting member 3 is locked against rotation, in that the pin 10 is of such length as to prevent the spheres 8 from passing in circumferential direction from one slot to another. However, in the zone A, due to the relatively greater inner diameter *a* of the housing or bushing 19, the spheres 8 are able to pass in circumferential direction from one slot into another, enabling thereby rotation of the selecting member 3. When the spheres—by rotation of the member 3—move over the distance *c*, Fig. 2, between two slots 7 the member 3 is locked against axial sliding movement, in that due to the length of the pin 10 the spheres are not able to move in axial direction upon the cylindrical wall of smaller diameter *b*. When the spheres 8 fall from the elevated part *c* into the guide slots 7 to a fixed rest-position by a snap-movement from the free zone A the relative operative angular position of the member 3 is indicated to the person operating the pencil by a click easily heard or felt.

The described locking means of the actuating mechanism locks the selecting member against undesirable axial sliding movements and indicates when it is in position to move axially. In the latter position the selecting member is locked against relative rotations, by the same locking means described.

The actuating button in combination with the locking means described may be, according to this invention, detachably coupled with the selecting member 3 and also removably attached to the housing, permitting thereby the provision of means on said actuator button which serve a useful purpose.

In Fig. 1 is shown an actuating button provided with means mentioned above. The fronts or opposed ends of the button and the selecting member are provided with radial toothings 11a and 3b meshing with each other when there is no lead in writing position in the feeder permitting as well known, the selecting member to be rotated, in that the spring 13 biases the selecting member against the actuator button 11 bringing thereby the radial toothings into mesh with each other. In the condition when there is a lead in writing position in the feeder, the button cannot rotate

the selecting member. The spring 23 presses the actuator button with its projections 21a against the annular top portion 19c of the bushing 19 which is part of the housing. The uncoupled condition of the actuator button and the selecting member 3 is advantageous in that the selecting member cannot be forced to rotate in its locked position, whereby damages to the mechanical pencil by improper manipulations is efficiently prevented.

The described coupling permits the use of an actuator button which is removably attached on the housing.

In Fig. 1 the button 11 is removably fastened on the housing and is provided with a conical hole 20 with a surface suitably made to sharpen a lead with the actuator button when removed from the pencil. The removability is accomplished by the collar 21 having integral or rigidly fastened projections 21a. This collar is rotatably disposed on a cylindrical portion of the button. The design permits moving the two opposite projections 21a into registering position with slot openings 22 on the annular top portion of the housing. This annular portion normally serves to retain the actuating button under the pressure of the springs 13 or 23. Shoulders 22a are integrally or rigidly fastened inside the annular top portion 19c so as to form depending lugs on each side of the slots 22. The projections 21a and said slot openings can be brought in registering position with each other. To attain this, the sleeve 21 is rotated until the projections 21a abut the shoulders 22a (see Fig. 5) on the annular top portion 19. The actuator button is pushed down until the projections 21a clear the lugs 22a, and are able to move into the slot-opening 22, whereupon the pressure of the coil spring 23 separates the button from the pencil.

Fig. 3 shows a modified design of the actuator button shown in Fig. 1. The rotatable sleeve of the modified actuator button is shaped to constitute an annular lead sharpener as shown in Fig. 3. In the use of the actuator button as a pencil sharpener the lead in writing position on the pencil is introduced into the hole 25a of the spring plate 25 against the pressure of the coil spring 25b and the button with the collar, rotated and simultaneously moved axially of the button towards the pencil, whereby the lead point is sharpened. The dust coming from the sharpening of the lead point falls through the channel 26.

Fig. 4 shows an actuator button with an outer part 28 which is permanently and rigidly attached to the selecting member 3, which may be provided with locking means such as shown in Figs. 1 and 2. Inside the button part 28, a part 27 is removably fastened; screw-threading is shown for this purpose; a resilient washer 30 of a material such as soft rubber prevents accidental loosening of the screw connection. In an obliquely disposed slot of the part 27 a plate-like lead sharpening plate 27a is disposed. A hole 29 provides for a passage from the bottom of the part 27 to the plate 27a, as shown. When the part 27 is being removed from the cylindrical part 28 it may be used as a sharpener for the lead of the pencil in that the lead is introduced into the hole 29, and the part 27 rotated by hand.

In Fig. 6 the selecting member 3 is shown attached to the feeder 14, 15. 16 is the lower part of the housing 1 which cooperates in well known manner with the feeder part 14. A sleeve 4 is rotatably fitted around the selecting member,

notably between the disk 6 and shoulders inside the lower part of the housing. The cells for the leads are shown at 2a. The selecting sleeve 4 is coupled with the selecting member 3 over a pin 17 thereof and a curved slit 18 through the wall of the sleeve 4, as shown. The sleeve 4 has through its cylindrical wall a longitudinal slit (not shown) of a width that equals the width of the cells for the leads. The selecting member 3 is provided with a slot 12 of a width which is also substantially equal to the width of a cell for the leads. The slot 12 corresponds axially exactly with the central passage of the feeder 14, which is rigidly attached to the lower end thereof. Co-operation of the disclosed actuating mechanism together with the mechanism which is actuated to select and guide a lead is as follows:

When a lead is in writing position in the feeder (dash-dotted lines in Fig. 6), the selecting member 3 is locked against rotation because in this position of the feeder 14 the spheres 8 are engaged in zone B of the guide-slots 7 in which position the pin 10 prevents the spheres from clearing the guide-slots 7. If it is desired to retire a lead in writing position into its cell the actuating button is pressed down while the pencil is held upside down whereby the feeder due to its resiliency opens and the lead is guided back to its cell by gravity, passing through the slit in the selecting sleeve 4 and the slot 12. During the sliding movement of the selecting member 3 the spheres 8 prevent rotation of the member 3.

When there is no lead in the feeder 14 the latter assumes the position shown in full lines. The spheres 8 are thereby placed to occupy the upper zone A of the guide-slots 7. In this position the spheres 8 ride resiliently over the guide-slots as set forth previously. When the spheres move between two guide-slots, the selecting member is locked against sliding movement. Each guide-slot determines a different cell of the leads, and permits therefore selection of any of the different leads in a cell. If the selecting member 3 is set for a lead to be brought into writing position the button 11 is pressed down to thereby rotate the selecting sleeve 4 and the slit thereof to register with the cell of the desired lead and also with the slot 12 in the selecting member itself. In the pressed-down position of the selecting member the feeder 14, due to its resiliency leaves 15, is opened. Hence a free passage from the cell of the lead to be put in writing position is established through which the lead in the upright position of the pencil passes by gravity. After the lead has been adjusted by hand to its proper writing position in the feeder 14, the button 11 is released, whereby the selecting member 3 and the feeder 14 are returned to the position which is indicated in broken line in Fig. 1, in which the spheres 8 remain engaged in the zone B of the guide-slots 7.

What I claim is:

1. An actuating mechanism for mechanical pencils which are composed of an outer housing, an actuating button, a selecting member slidably and rotatably disposed within said housing, the housing formed with cells arranged longitudinally, lead feeding means comprised of a feeder resiliently disposed at the bottom of the housing, and auxiliary mechanism to admit and guide a lead from a cell into said feeder or to return a lead in writing position in said feeder back into the cell, wherein the selecting member is provided with locking means, and the inner cylindrical surface of the housing is formed at its upper end with longitudinal guide slots, and said locking

means in said selecting member placed axially for engagement with said guide slots, while said selecting member is moved in axial direction, said guide slots extending over two different inside diameters of said inner cylindrical surface and thereby subdivided axially into an upper and lower zone, said upper zone having a greater inside diameter than said lower zone, said locking means comprising a cross-bore in said selecting member, spring means, a pin and at least one sphere in said cross-bore, said sphere protruding from said cross-bore beyond the outer surface of the selecting member, said spring means adapted to press said sphere towards said guide slots, said pin by its length adapted to limit displacement of the sphere towards the inside of said cross-bore to maintain said spheres engaged with said guide slots in said lower zone, while permitting said sphere to resiliently ride over said guide slots in their upper zone, shoulders of said guide slot walls between the upper and lower zone cooperating with said spheres to prevent axial movement of the selecting member during rotation thereof when said spheres are moved over the side walls of the guide slots, and spring means opposed to axial movement of the selecting member and at such movement after the actuating button has been released to return the selecting member to its initial position.

2. In a mechanical multi-lead pencil having a sleeve-like outer housing, a plurality of longitudinally extending cells within said housing, each said cell being adapted to contain a lead, lead feeding means within said housing, said means being axially slidable to protrude from the lower end of said housing, and a selector mechanism operable to permit the lead contained in each cell to pass from one of said cells into said feeding means, and in return, said selecting mechanism including a selecting member, said member being axially slidable and rotatable within the housing and extending towards the upper end of said housing, an arrangement whereby said selecting member may be alternatively locked against rotation or rotated as desired, said arrangement comprising a plurality of guide slots, each formed as a longitudinal continuation within the upper portion of said housing of one of said cells, recessing of the radially inner portion of the walls defining said guide slots at the upper extremity thereof to provide said continuation into a zone of greater inside diameter and a zone of lesser inside diameter, locking means for said selecting member, said locking means comprising a crossbore in the portion of said selecting member contiguous to said slots, at least one sphere protruding from said crossbore, a spring in said crossbore, said spring serving to force said sphere radially outwardly toward said slots, and a pin in said crossbore, said pin being of such length as to limit displacement of the sphere into the said crossbore to engage said sphere with the portion of said guide slots in the zone of lesser inside diameter, while permitting said sphere to ride resiliently over said guide slots in said zone of greater inside diameter, springs means urging said selecting member upward to dispose said sphere in said zone of greater inside diameter, and an actuating button insertable through the upper end of said housing and removable therefrom, said button extending axially within the housing, that portion of said button so extending within said housing being provided with means to coact with said selecting member to effect rotation thereof when said sphere is positioned in

the zone of greater inside diameter, whereby the application of pressure on said button in opposition to said spring means forces said sphere down a guide slot and out of the zone of greater inside diameter and brings a lead into the feeding means.

3. The arrangement as described in claim 2 wherein the actuating button includes a coaxial sleeve about that portion of the button which extends axially into the housing, said button being rotatable relative to said sleeve, radially outwardly extending projections on said sleeve, an annular flange on the top of said housing, said flange being provided with slot openings flanked by shoulders through which openings said projections may be passed by axial movement of said

button when said projections are in registry with said openings, and spring means between said selecting member and the lower end of said button, whereby said button may be removed by the pressure of said spring means when the projections are placed in registry with said slot openings.
